UNITED STATES PATENT OFFICE.

GUNNAR ELIAS CASSEL, OF STOCKHOLM, SWEDEN, ASSIGNOR TO AKTIEBOLAGET GYRO, OF STOCKHOLM, SWEDEN, A CORPORATION OF SWEDEN.

BREAST-DRILL.

1,387,921.

Specification of Letters Patent. Patented Aug. 16, 1921.

Application filed February 17, 1920. Serial No. 359,478.

To all whom it may concern:

Be it known that I, GUNNAR ELIAS CASSEL, a citizen of the Kingdom of Sweden, residing at Stockholm, Sweden, have invented new and useful Improvements in Breast-Drills, of which the following is a specification.

This invention relates to a breast-drill in which a friction-ratchet gear is employed for the transmission of power from the brace to the chuck.

In my copending patent application Ser. No. 359,479: I have described a friction-ratchet gear comprising annular elements mounted on a common shaft and having a helicoidal friction surface between the driving and the locking elements and a conical friction surface between the locking and the driven elements. According to the above said patent application the angles of said friction surfaces are so proportioned as to permit the friction-ratchet gear to work without any back-lash in the forward movement and without any shock in the reverse movement.

The object of this invention is to enable the use of such a friction ratchet gear in connection with a breast-drill. One feature of the invention, therefore, consists in making the friction-ratchet gear reversible, so that a uni-directed movement in the one direction or the other may be imparted to the chuck by turning the brace back and forth.

More nearly stated, the said feature involves that the driving and the locking elements of the friction ratchet gear are provided with two friction surfaces or two sets of friction surfaces one of said surfaces or sets of surfaces operating for the one direction of movement, while the other surface or set of surfaces operates for the other direction of movement.

Another feature belonging to the above stated is the provision of means for bringing the desired surfaces or sets of surfaces into operation.

Still other features of the invention will be clear from the following description.

In the accompanying drawings, a breast-drill embodying this invention is illustrated. Figure 1 is a side-elevation of the breast-drill. Fig. 2 is a longitudinal section on a larger scale through the friction-ratchet gear and the chuck of the drill. Fig. 3 is

a longitudinal section through the casing 55 for the friction ratchet gear. Fig. 4 is a plan view of said casing. Fig. 5 is a section on the line A—A in Fig. 2. Fig. 6 is a section on the line B—B in Fig. 2 with parts shown in plan view. Figs. 7, 8 and 9 are 60 elevation, longitudinal section and end-views, respectively, of the driving element of the friction-ratchet gear. Figs. 10, 11 and 12 are corresponding views of the locking element of the friction-ratchet gear. 65 Figs. 13 and 14 are elevation and end-views, respectively, of an adjusting member of the friction-ratchet gear. Figs. 15 and 16 are longitudinal section and cross-section on the line C—C in Fig. 15, respectively, of same 70 member. Fig. 17 shows the inner surface of the elements shown in Figs. 7—9 and 10—12 in unfolded state and in engagement with one another.

The brace 1 of the breast-drill shown carries in the known way the handles 2 and 3. The lower end of the brace engages in a sleeve 4 and is rigidly connected thereto by means of a locking pin 5. The sleeve 4 is formed integral with another sleeve 6 having a larger diameter than that of the sleeve 4 and forming right angles thereto, as is best shown in Fig. 3.

The sleeve 6 carries a chuck and a friction ratchet gear for the transmission of 80 power from the brace 1 to said chuck. The sleeve 6 is closed at its lower end by a bottom plate 7 provided with a central opening through which extends a spindle 8. The spindle 8 rests on the said bottom with an 90 enlarged portion comprising a lower cylindrical part 9 and an upper conical part 10. Extending upwardly from the cone 10 is a stem or spindle 11 the diameter of which is less than that of the spindle 8. 95

The cone 10 supports an annular member 12 having a conical recess in its lower end in which the cone fits, the member 12 also surrounding the lower portion of the stem 11. The part of the member 12 surrounding 100 the stem 11 has a reduced outer diameter relative to the diameter of the lower portion of said member 12 so as to form a shoulder 13. The upper reduced portion of the member 12 is formed with outwardly extending 105 projections 14 at diametrically opposite points. The upper end surface of the member 12 is cam-shaped and consists of heli-

coidal surfaces 15 and 16 inclined alternatingly in opposite directions, as shown in Fig. 17.

Resting on the shoulder 13 of the ring 12 5 is a ring 17 rotatably mounted in the sleeve 6. Said ring 17 is shown in details in Figs. 13-16. The ring 17 is formed in its lower surface with two diametrically opposed openings 18. In said openings the projections 10 14 of the ring 12 are adapted to engage, as shown in Fig. 5. In the sides of the openings 18 there are formed borings 19 (Fig. 16) adapted to receive springs 20', 20² bearing against the sides of the projections 15 14 (Fig. 5). For limiting the rotation of the ring 17 relatively to the sleeve 6, the ring 17 is formed with a recess 21 (Fig. 16) on its outer side to be engaged by a stop screw 22 inserted in the sleeve 6 (Figs. 2 20 and 5).

Inserted in the upper end of the sleeve 6 is a cover or plug 23 provided with a downwardly extending cylindrical projection 24. The plug 23 is shown in details in Figs. 7-9. 25 The projection 24 depends into the space between the ring 17 and the stem 11 and is formed on its lower edge with a cam surface corresponding to the cam surface 15, 16 of the ring 12 and consisting of helicoidal surfaces 20 25, 26, inclined alternatingly in opposite directions said surfaces being adapted to coöperate with the helicoidal surfaces 15, 16. The helicoidal surfaces 15, 16, 25, 26 are so arranged as to permit a certain relative rotation of the members 12, 24, so that only the surfaces 15 and 25 or the surfaces 16 and 26 may be in contact with each other at the same time.

Mounted in the sleeve 4 is a bolt 27 which 40 is both rotatable and axially movable. Said bolt 27 extends into the sleeve 6 and carries at its inner end a cam 28 made integral with the bolt. Loosely engaging the said end of the bolt 27 is a screw 29 carrying a diametrically arranged wedge 30 outside the end of the bolt. The cam 28 engages a lateral opening 31 (Figs. 13-16) in the ring 17, and the wedge 30 extends through a lateral opening 32 (Figs. 7-8) formed in the 45 member 24. The stem 11 is formed with a recess 33 (Fig. 6) to be engaged by the wedge 30.

Secured in a transverse hole in the bolt 27 is a screw pin 34 extending through a slot 55 35 formed in the sleeve 4, said pin being attached with its outer end to a serrated ring 36 rotatably and slidably mounted on the sleeve 4. The slot 35 extends around the upper half of the periphery of the sleeve 4, as 60 shown in Figs. 3 and 4. Midway between the ends of the slot 35 an axial recess 37 is formed in the wall of the slot nearest to the sleeve 6, similar recesses 38, 39 of a smaller axial extension being formed at the ends of 65 the slot 35. Situated between the ends of

the brace 1 and the bolt 27 in the sleeve 4 is a pressure spring 40, tending to move the bolt 27 toward the stem 11.

The spindle 8 extending through the bottom 7 of the sleeve 6 carries a chuck below 70 said bottom. As shown in Fig. 2, said chuck comprises a ring 42 surrounding the spindle and being secured thereto by means of the pin 41. The ring 42 is threaded on its outer surface and is screwed into a sleeve 43, 75 formed at its lower end with a conical mouth 44, surrounding the conical jaws 45 mounted in the sleeve 43 and engaging the lower end of the spindle 8. By screwing the sleeve 43 upwardly or downwardly the jaws 45 may 80 be moved together or apart.

The operation of the breast-drill is as follows: Assuming the parts are in the position shown in Fig. 2, a rigid connection exists between the brace 1 and the stem 11 so 85 that the stem and thus the spindle 8 with the chuck will be moved with the brace, whether the brace is rotated in the one direction or the other. In said position the pin 34 engages the central lateral recess 37 of 90 the slot 35; the wedge 30 being, therefore, in engagement with the slot 33 in the stem 11. Now the parts 12 and 17 are in the relative position shown in Fig. 5 in which the projections 14 are centered in the openings 95 18, and the springs 20', 20² counterbalance each other.

If it is desired to rotate the chuck in the direction indicated by the arrow *a* in Fig. 1 by turning the brace back and forth, the 100 operator grasps the ring 36 and moves the same to the right (Fig. 2) thereby removing the pin 34 from its engagement in the recess 37 whereupon the ring 36 is turned in clockwise direction, till the pin 34 snaps 105 into the recess 38. In the longitudinal movement of the ring 36, the wedge 30 was brought out of engagement with the recess 33 in the stem 11, and said engagement will not be restored when the pin 34 snaps 110 into the recess 38, as said recess is too shallow to allow such engagement. During the turning of the ring 36 with the bolt 27 the wedge 30 is maintained in its position in register with the recess 33 due to its engagement in the opening 32 in the member 24. This is possible on account of the loose engagement of the screw 29 in the bolt 27. 115

Upon the turning of the bolt 27 the cam 28 was moved from its inactive position 120 shown in Fig. 2 into the position shown in Fig. 6. In said movement the cam 28 acts on the ring 17 and turns same in clockwise direction from a central position, in which the opening 31 is in axial register 125 with the bolt 27, into the position shown in Fig. 6. This movement of the ring 17 causes the springs 20' to turn the ring 12 in the direction indicated by the arrow *b* in Fig. 17 into a position relative to the 130

member 24, in which the inclined surfaces 15 are in contact with the inclined surfaces 25, as shown in Fig. 17, the springs 20' being then further compressed and tend to still 5 move the ring 12 in the same direction, but as the member 24 is stationary, said action of the springs will cause the member 12 to slide on the surfaces 15 so as to be pressed against the cone 10 with a gentle pressure 10 securing a good contact at the inclined surfaces 15, 25 as well as at the conical surfaces.

The brace 1, being then turned in the direction of the arrow *a* in Fig. 6, will take 15 the casing 4, 6 and the member 24 with it. Said movement of the member 24 is indicated by the arrow *a* in Fig. 17. The inclined surfaces 25 are thus caused to exert a downwardly directed pressure on the member 12. Due to this pressure the member 20 12 will be pressed against the cone 10 so as to interlock the members 24, 12 and 10. As a good contact was secured at the contact surfaces by the action of the springs 25 20' previous to the operation of the brace 1, the said interlocking will take place without any back-lash at the same instant that the brace is operated.

In returning the brace, the pressure from 30 the member 24 on the member 12 will cease immediately thereby releasing the interlocking of the parts and permitting the compressed springs 20' to immediately take with it the ring 12, which will in this movement 35 slide on the cone 10. The returning of the brace will thus be effected without the need of any power for releasing the interlocking of the parts of the friction ratchet gear. In other words, the friction ratchet gear 40 operates without any back-lash in the forward movement and completely without any shock in the reverse movement.

If it is desired to turn the chuck in the opposite direction to that indicated by 45 the arrow *a* in Fig. 1 by oscillating the brace 1, the ring 12 is moved in counter-clockwise direction, until the pin 34 snaps into the lateral recess 39. This will result in a release of the springs 20' and a compression 50 of the springs 20' which will then move the ring 12 to effect contact between the inclined surfaces 16 and 26.

For attaining the above said purpose, viz., no back-lash in the forward movement and 55 no shock in the reverse movement, the friction ratchet gear is so constructed as to answer to the following conditions: The clutch member 12 is made self-releasing with respect to the helicoidal friction surfaces, 60 inasmuch as the angle of inclination of said surfaces is greater than twice the angle of friction of same surfaces. Furthermore, the clutch member 12 is made self-releasing with respect to the conical friction surface inasmuch as the top angle of the conical surface 65

is greater than twice the angle of friction of said surface. Said two conditions will secure the self-releasing action of the friction ratchet gear upon reverse movement of the driving element of said gear. In order 70 that the device may be self-locking in the forward movement of the driving element, that is when the clutch element 12 is subjected to pressure from the member 24, it is necessary that the angle of inclination 75 of the helicoidal or inclined surfaces is less than the sum of the angle of friction of said surfaces and the ideal angle of friction of the cone. A more detailed explanation of said conditions is given in my copending patent application Serial No. 359,479.

Having now described my invention, what I claim as new is:—

1. In a breast-drill, the combination of a brace, a chuck, a casing rigidly connected 85 with said brace, and a reversible friction ratchet gear in said casing for imparting a unidirected movement to the chuck upon an oscillating movement of the said brace.

2. In a breast-drill, the combination of a 90 brace, a sleeve-shaped casing rigidly connected to said brace, a spindle mounted in said casing and carrying a chuck outside thereof, a cone on said spindle, a ring loosely mounted on said cone and having inclined 95 friction surfaces on its upper end, another ring rigidly connected to the said casing and having inclined surfaces on its lower side for engaging with the said first-mentioned inclined surfaces.

3. In a breast-drill, the combination of a 100 brace, a casing rigidly connected to said brace, a chuck carried by said casing, a reversible friction ratchet gear mounted in said casing for imparting a unidirected movement to the chuck upon an oscillating movement of the brace, and means for reversing 105 said friction ratchet gear.

4. In a breast-drill, the combination of a brace, a casing rigidly connected to said 110 brace, a spindle mounted in said casing and carrying a chuck outside thereof, a cone on said spindle, a ring loosely mounted on said cone and having in its upper end one set of inclined friction surfaces for each direction of movement, another ring rigidly connected to said casing and having corresponding sets of inclined friction surfaces for engagement with said first mentioned surfaces, and means for operating the said first-mentioned ring to bring it into contact with the one set of inclined surfaces or the other on the said other ring.

5. In a breast-drill, the combination of a 120 brace, a casing rigidly connected to said brace, a spindle mounted in said casing and carrying a chuck, a cone on said spindle, a ring loosely mounted on said cone and having two sets of inclined friction surfaces, another ring rigidly connected to the said casing and 125 130

having corresponding sets of inclined friction surfaces, springs acting on said first-mentioned ring, and means for causing the springs to move the said ring into engagement with one set of inclined surfaces or the other of said other ring.

6. In a breast-drill, the combination of a brace, a casing rigidly connected to said brace, a chuck carried by said casing, a reversible friction ratchet gear in said casing for imparting a unidirected movement to the chuck upon oscillation of the brace, springs for reversing said gear, a ring loosely mounted in said casing for the operation of said springs, and a manually controlled cam for operating said ring.

7. In a breast-drill, the combination of a

brace, an angularly shaped sleeve rigidly connected to said brace, a spindle mounted in said sleeve and carrying a chuck outside thereof, a reversible friction ratchet gear between said spindle and said sleeve, springs for reversing said gear, a ring mounted concentrically to said spindle for operating said springs, a manually controlled cam rotatably and longitudinally movable at right angles to said spindle for operating the said ring, and a projection on said cam for directly engaging in said spindle, when the cam is out of operation.

In testimony whereof I have signed my name.

GUNNAR ELIAS CASSEL.
